(57) **CLAIM**

The ornamental design for a hand portable air compressor, as shown and described.

DESCRIPTION

FIG. 1 is a top/front perspective view of a hand portable air compressor showing my new design.

FIG. 2 is a front view thereof.

FIG. 3 is a rear view thereof.

FIG. 4 is a left side view thereof.

FIG. 5 is a right side view thereof.

FIG. 6 is a top side view thereof.

FIG. 7 is a bottom view thereof.

FIG. 8 is a rear perspective view thereof; and,

FIG. 9 is a bottom/front perspective view thereof.
